UNITED STATES PATENT OFFICE.

ERNEST N. DORING, OF NEW YORK, N. Y.

WARDROBE-BEDSTEAD.

SPECIFICATION forming part of Letters Patent No. 244,567, dated July 19, 1881.

Application filed October 7, 1880. (No model.)

To all whom it may concern:

Be it known that I, ERNEST N. DORING, of the city, county, and State of New York, have invented a new and useful Improvement in 5 Wardrobe-Bedsteads, of which the following is a specification.

Figure 1 is a rear elevation, partly in section, of the improvement shown in position for use. Fig. 2 is a sectional side elevation 10 taken through the line *x x*, Fig. 1. Fig. 3 is an elevation, partly in section, showing the weight-box supported from the floor. Fig. 4 is a sectional end elevation of the weight-box, taken through the line *y y*, Fig. 3.

15 The object of this invention is to furnish wardrobe-bedsteads so constructed that the frames or cases of the bedsteads and the weight-boxes can be readily disconnected, when desired, for convenience in moving the bedstead 20 from place to place.

Similar letters of reference indicate corresponding parts.

A represents the side boards of the head or stationary part of a wardrobe-bedstead.

25 B are the side boards of the folding or movable part.

C is the base-board of the stationary part. The middle rear part of the base-board C is cut away to receive the weight-box D and 30 serve as a guide to stop the said weight-box in proper position to be taken up by the folding part B when lowered. The lower side of the ends of the weight-box D are rabbeted, as shown in Figs. 1 and 3, to receive the side 35 parts of the base-board C. The rabbets of the weight-box D are made of such a depth that the weight-box D will be supported free from floor and in such a position that the hooks E of the side boards, B, will engage with the 40 pivots F attached to the ends of the weight-box D when the movable part is lowered.

The weight-box D is divided into three compartments by cross-partitions G, a central compartment to receive the weight-bricks H, and 45 two end compartments to receive the blocks I. The blocks I are pivoted to the sides of the weight-box D and have their upper ends the heavier. The bottoms of the end compartments of the weight-box D are cut away, leaving 50 shoulders at the outer ends, as shown in

Figs. 1 and 3, so that when the blocks I are turned into a horizontal position their heavier ends will rest upon the said shoulders and hold the said blocks in place. The blocks I are made of such a length that when they are turned 55 into a vertical position, with their lower ends upon the floor, the weight-box D will be supported clear of the base-board C, as shown in Fig. 3, and the bedstead can be moved from one place to another without moving the weight-box. With this construction, when the bedstead is to be moved the movable part is 60 turned down, raising the weight-box D. The pivoted blocks I are then turned into a vertical position and the movable part is again 65 raised, which leaves the weight-box standing upon the blocks I and free from the base C, so that the bedstead can be easily moved from its place without having to carry the weight-box with it. The weight-box can then be 70 placed where it is desired to place the bedstead, and the said bedstead can be moved over it until the edge of the base C at the bottom of its cut comes in contact with the said weight-box. The movable part of the bedstead is then lowered to raise the weight-box, 75 the blocks I are turned into a horizontal position, and the movable part of the bedstead is raised, leaving the weight-box resting upon the end parts of the base C. 80

Having thus fully described my invention, I claim as new and desire to secure by Letters Patent—

1. In a wardrobe-bed, the combination, with the folding part B, carrying hook E, and the 85 base-board C, cut away at its middle rear part, of the weight-box D, rabbeted on the lower side of its ends and provided with the pivot F, for the purpose specified.

2. In a wardrobe-bed, the weight-box D, provided with blocks I, pivoted to its sides, and having their upper ends heaviest, and with end compartments cut away at bottom and provided with shoulders at the outer ends, for the purpose specified. 90

ERNEST N. DORING.
